Primary Examiner — Clint A Samuel(74) *Attorney, Agent, or Firm* — Orbit IP, LLP; Marc G. Martino(57) **CLAIM**

The ornamental design for a lighting panel as shown and described.

DESCRIPTION

FIG. 1 is a top plan view of a lighting panel embodying my new design;

FIG. 2 is a bottom plan view of the structure thereof;

FIG. 3 is an isometric perspective view mostly showing the top of the structure thereof;

FIG. 4 is another isometric perspective view mostly showing the top of the structure thereof;

FIG. 5 is an isometric perspective view mostly showing the bottom of the structure thereof; and,

FIG. 6 is a side elevation view of the structure thereof. The broken lines depict environmental subject matter, are for illustration only and form no part of the claimed design.
